United States Patent Office

Des. 193,360
Patented Aug. 7, 1962

193,360

HARP

Samuel O. Pratt, New York, N.Y., assignor to Lyon &
Healy, Inc., Chicago, Ill., a corporation of Illinois

Filed Dec. 20, 1961, Ser. No. 67,997

Term of patent 14 years

(Cl. D56—1)

Fig. 5.

Fig. 6.

FIGURE 5 is a fragmentary top plan view looking in the direction of the arrows 5—5 in FIG. 4; and

I claim:

The ornamental design for a harp, as shown.
